[57] CLAIM

The ornamental design for a holder for use in making rubbing-type reproductions, substantially as shown and described.

DESCRIPTION

FIG. 1 is a perspective view of a holder for use in making rubbing-type reproductions showing our new design;

FIG. 2 is a right side elevational view thereof;

FIG. 3 is a rear elevational view thereof; and

FIG. 4 is a bottom plan view thereof.

FIG. 2

FIG. 3

FIG. 4
